UNITED STATES PATENT OFFICE.

JOHN F. GRACE, OF KEARNEY, NEW JERSEY, ASSIGNOR TO WORTHINGTON PUMP AND MACHINERY CORPORATION, OF NEW YORK, N. Y., A CORPORATION OF VIRGINIA.

CONDENSER SYSTEM.

1,417,515.

Specification of Letters Patent. Patented May 30, 1922.

Application filed November 24, 1920. Serial No. 426,142.

To all whom it may concern:

Be it known that I, JOHN F. GRACE, a citizen of the United States, residing at Kearney, county of Hudson, and State of New Jersey, have invented certain new and useful Improvements in Condenser Systems, fully described and represented in the following specification and the accompanying drawings, forming a part of the same.

10 This invention relates to improvements in condenser systems of that class employing a centrifugal hot-well pump with two stages on the same shaft and the first stage delivering to the intercooler of a two-stage air ejector, so as to operate against a less head than the second stage.

I provide for artificially increasing the head on the first stage of the pump, and I preferably make this artificial head adjustable to secure the best operation and greatest economy under all conditions.

For a full understanding of the invention, a detailed description of preferred constructions for carrying the same into effect and arranged for cooperation with a surface condenser, will now be given in connection with the accompanying drawings, and the features forming the invention then specifically pointed out in the claims.

30 In the drawings—

Figure 1 shows in end elevation a surface condenser and in partial section my improved arrangement of two-stage steam ejector with intermediate jet condenser and adjustable spring operated spray valve for the first stage of the two-stage hot-well pump; and.

Figure 2 is a vertical section of a modified construction.

40 Referring now to the drawings, and especially to Figure 1, the numeral 10 indicates generally a condenser of the surface type, with a first stage steam ejector 12 withdrawing air from the outlet 11 and delivering through nozzle 12' to a jet intercooler or condenser 13, and the second stage steam ejector 14 withdrawing air from the intercooler through pipe 15 and delivering against atmospheric pressure. The first stage of an ordinary two-stage centrifugal pump 16 takes its suction through pipe 17 from the condenser hot-well 18, and delivers to the intercooler 13 through pipe 19 having therein a spray valve 20 which opens 50 against the pressure of a spring 1, the ten-

sion of which is adjustable by nut 2 to secure the proper operation of the pump, the pressure required to open this valve preferably being the least pressure giving satisfactory operation under all conditions. 60 Water of condensation from the intercooler 13 is withdrawn by the second stage of the hot-well pump through pipe 22 and delivered to a feed water heater or supply tank, as preferred. Vent pipe 23 connects 65 the pump casing with the upper part of the hot-well to free the pump of air, as usual.

Other means may be used for suitably increasing the head on the first stage of the pump to secure efficient operation. In Fig. 70 2 I have shown, for example, a packed plunger valve 24 in pipe 19 opening against atmospheric pressure, and any other suitable form of back pressure valve may be used. In the construction of Fig. 2, the discharge 75 from pipe 19 to the intercooler is through nozzle 25 to which the steam ejector nozzle 12' discharges.

It will be understood that various changes and modifications in the constructions above 80 described and shown may be made without departing from the scope of the claims, and that the invention is not to be limited to use in connection with condensers of the surface type. While the invention is of es- 85 pecial importance as applied to condenser systems such as described, the feature of artificially increasing the head on one stage of a two-stage pump to equalize the head on the two stages is of more general appli- 90 cation and is broadly claimed.

What is claimed is:

1. The combination with a condenser system including multistage steam air ejector devices, an intermediate jet condenser or 95 intercooler, and a two-stage centrifugal hot-well pump, the first stage of which delivers to the intercooler, of means interposed in the delivery of the first stage of the hot-well pump for maintaining an increased 100 head thereon to secure the efficient operation of the pump.

2. The combination with a condenser system including multistage steam air ejector devices, an intermediate jet condenser or 105 intercooler, and a two-stage centrifugal hot-well pump, the first stage of which delivers to the intercooler, of adjustable means interposed in the delivery of the first stage of the hot-well pump for maintaining an ad- 110

justable increased head thereon to secure the efficient operation of the pump.

3. The combination with a condenser system including multistage steam air ejector devices, an intermediate jet condenser or intercooler, and a two-stage centrifugal hot-well pump, the first stage of which delivers to the intercooler, of a valve closed by spring pressure through which the said 10 first stage of the hot-well pump delivers to the intercooler, and means for adjusting

the pressure on the valve to secure the pump head desired.

4. The combination with a two-stage pump, one stage of which delivers against a 15 lower head than the other, of means for increasing the head on the stage delivering against the lower head to secure the proper operation of the pump.

In testimony whereof, I have hereunto 20 set my hand.

JOHN F. GRACE.
